UNITED STATES PATENT OFFICE.

LEWIS HENRY LLOYD, OF BLOOMINGTON, ILLINOIS.

APPARATUS FOR RAILWAY MAIL-DELIVERY.

1,281,180.

Specification of Letters Patent.

Patented Oct. 8, 1918.

Application filed May 11, 1918. Serial No. 233,896.

To all whom it may concern:

Be it known that I, LEWIS HENRY LLOYD, a citizen of the United States, residing at Bloomington, in the county of McLean and 5 State of Illinois, have invented certain new and useful Improvements in Apparatus for Railway Mail-Deliveries; and I do hereby declare the following to be a full, clear, and exact description of the invention, such as 10 will enable others skilled in the art to which it appertains to make and use the same.

The present invention relates to improvements in apparatus for railway mail delivery, and has for an object to provide an 15 exceedingly compact device adapted to be carried by mail cars in which the mail receiving and delivery parts are arranged beneath the car out of the way of the mail clerks, and the operating mechanism for 20 such parts is arranged to take up a minimum of space in the car.

It is another object of the present invention to provide apparatus for railway mail delivery which will be effective in transferring mail sacks to railway cars passing stations at high rates of speed, and at the 25 same time provide for the delivery of other mail sacks at such stations.

In the accompanying drawings forming a 30 part of this application, and in which similar reference symbols indicate corresponding parts in the several views:

Figure 1 is a vertical sectional view through a portion of a railway mail car and 35 a portion of track, and showing an apparatus constructed in accordance with my present invention.

Fig. 2 is a horizontal sectional view taken on the line 2—2 in Fig. 1.

Fig. 3 is a vertical sectional view taken on the line 3—3 in Fig. 2.

Fig. 4 is a similar view taken on the line 4—4 in Fig. 1.

Fig. 5 is an enlarged sectional view 45 through a portion of the car bottom and track with the improved apparatus shown partly in elevation and partly in section.

Fig. 6 is a cross sectional view through the track and trough.

Fig. 7 is a fragmentary view of the trunk 50 operating parts in one position; and

Fig. 8 shows the same parts in another position.

Referring more particularly to the drawings, 55 1 designates generally a railway mail car which is adapted to run on the track 2.

At each station I provide a metallic or other trough 3, which I sink beneath the level of the ties and between the rails 2. This trough may have any suitable depth and is 60 adapted to receive the mail bags 4. The end walls 5 and 6 of the trough are made sloping, as shown in Fig. 1, for a purpose to be hereinafter described. The upper ends of the sloping walls 5 and 6 may be continued in the form of platforms 7 and 8 resting on the tops of the ties in a position elevated over the trough 3, and such platforms preferably have their opposite ends bent down, as indicated at 9 and 10. 70

In the mail car 1 is supported a trunk 11 having its free movable end adapted to dip down into the trough and provided with a roller 12 which may bear on the trough bottom to ease its passage thereover. A 75 curved lip 13 on the extreme end of the trunk 11 is adapted to come into contact with the bottom of the trough so as to engage beneath the mail sacks 4 and guide them into said trunk 11. The trunk 11 is 80 hinged, as indicated at 14, to a metal receiver 15 with which its hinged end communicates. The receiver 15 is mounted beneath the floor of the car and communicates with said car through a top opening which 85 is closed by a door 16 having a handle 17 which may be opened to remove the mail sacks.

A band 18 goes about the free end of the trunk 11, such band being formed with or 90 connected to a tongue 19 to which is pivotally connected the bifurcated lower end of a rod 21. This rod 21 is adapted to occupy a recess 22 in the floor 23 of the car, as shown to better advantage in Fig. 5, where 95 such rod will be out of the way and will hold the free end of the trunk 11 in the elevated inoperative position. The bifurcated end 20 of this rod 21 is formed with one or more extensions 24 having perforations 25 100 through which it is adapted to engage a catch 26 pivoted, as indicated at 27, in a second recess in the car floor and normally projected by a spring 28 so as to cause the catch to engage in the perforations 25 and 105 thereby lock the trunk in the upper position. A projection 29 on said catch 26 is provided to be engaged by the foot of one of the mail clerks, whereby the catch may be disengaged from the perforations 25 and the 110 rod 21 permitted to be elevated to the vertical position so that the trunk 11 may be

lowered. The hand-hold 30 is provided on the end of the rod 21 for convenience in operation.

There is also provided a mail delivery box 31, also mounted beneath the floor 23 of the car and to the rear of the receiver 15; such mail delivery box 31 being closed by a hinged door 32 having the handle 33 whereby the door may be opened to admit the 10 mail sacks, as indicated in Fig. 5. This mail delivery box 31 is provided with an inclined drop bottom 34 to which are attached the arcuate rods 35, the same having sliding movement through openings in brackets 36 15 mounted on the rear of said mail delivery box 31.

Coil springs 37 are wound about the rods 35 and bear against the brackets 36 in such a manner that they tend to force the 20 drop bottom 34 to the closed position shown in Fig. 5 and to yieldingly hold same in the closed position. At 38 is shown an extension on the drop bottom 34 which is adapted to be connected by a chain or other flexible 25 connection 39 which passes over a pulley 40 to one arm of a bell crank lever 41 pivoted, as indicated at 42, and having its other arm 43 coupled to an operating chain or cord 44. This chain or cord 44 is likewise adapted to 30 rest in a longitudinal groove in the floor 23 of the car so as to be out of the way of the mail clerks.

A ring or other handle 45 on the rod 44 serves as a means whereby the same may be 35 operated.

The operation of the invention is substantially as follows:

Mail to be transferred to moving trains is loaded into the sacks 4 and these sacks 40 placed in the troughs 3 at the respective stations. Mail sacks to be delivered are placed in the mail delivery box 31 on the car through the door 32 thereof, and are held therein until the proper destination is 45 reached.

As the car 1 approaches a station from which the mail sacks 4 are to be taken, and to which the mail sacks in the mail delivery box 31 are to be delivered, a mail clerk in 50 the car will first kick the projection 29 to release the latch 26 which will permit him to raise the rod 21 out of the recess 23 of the car floor to the vertical position, after 55 which he will lower the free end of the trunk 11 until the roller 12 strikes the inclined end 10 on the platform 8. It is preferable that the clerk exert a slight downward pressure on the rod 21 to hold the receiving mouth of said trunk close against the platform and trough. As the car proceeds, the 60 roller 12 will ease the passage of the trunk over the platform 8 and down the sloping end 6 into the trough 3, where the open receiving end of said trunk will come into contact with the mail sacks 4 deposited in said

trough, and will gather same up and force such sacks by the motion of the car into the receiver 15, where they may be removed by the mail clerk by opening the cover 16. The free end of the trough will strike the sloping end wall 5 and be again raised to elevated position, at which time the operator may drop the rod 21 into the recess 22, and the latch 26 may be arranged to automatically reengage the perforations 25 so as to lock the parts again in the inoperative position.

I prefer to provide toggle rods 46 and 47 connected together, as indicated at 48, and the rod 46 being pivoted, as indicated at 49, to the car, while the other rod 47 is pivoted at 50 to the trunk 11. If desirable two of these toggle rods may be employed, one at each side of the trough and when in the lowermost position, where the trunk is in the trough 3, the rods will extend in alinement to thereby steady such free end of the trough and provide a support therefor, which will take up most of the shocks and jars that would otherwise devolve on the hinge 14.

As the car is receiving the mail sacks 4, the mail sacks in the delivery box 31 may be deposited in the trough 3 by the operation of pulling upon the chain or cord 44. By pulling forwardly on this chain the bell crank lever is rocked on the pivot 42 and exerts a pull on the chain or flexible connection 39. This causes the drop bottom 34 to be opened in opposition to the springs 37 and allows the mail sacks in the box 31 to drop out into the trough 3. When the chain or cord 44 is released and allowed to drop back into its groove in the floor, the springs 37 will again come into play and force the bottom 34 closed. Substantially the above described operations are repeated at each station.

It is obvious that those skilled in the art may vary the details of construction and arrangements of parts without departing from the spirit of my invention, and therefore I do not wish to be limited to such features except as may be required by the claims.

I claim:

1. In an apparatus for railway mail delivery, the combination of a trough arranged along the roadway, a mail bag receiver carried by a mail car, a movable trunk in communication with the receiver and having one end arranged to dip down into the trough to catch the mail sacks therein, a tongue having connection to the free end of the trunk whereby to support same, a rod pivoted to said tongue, said rod being arranged in the mail car and adapted to extend substantially horizontally to hold the trunk in the elevated position, a catch pivoted on the car for engaging a part of said rod to hold same in the inoperative position, means for operating said catch whereby it may be withdrawn from the rod to permit

the latter to be raised and the trunk to be lowered thereby, substantially as described.

2. In an apparatus for railway mail delivery, the combination of a trough extending along the roadway and having inclined ends, elevated platforms extending from said ends, a mail bag receiver carried by a mail car, a trunk having a pivotal movement and in communication with the receiver, a tongue connected to support the free end of said trunk, a rod pivoted to said tongue whereby the trunk may be held in the elevated position or lowered so as to enter said trough, a catch to hold said rod in the inoperative position where the trunk is raised, and braces connected between the forward part of the trunk and the car to brace the latter, substantially as described.

3. In an apparatus for railway mail delivery, the combination of a trough built in the roadway and having sloping ends, platforms extending from the sloping ends and having downwardly bent extremities, a mail bag receiver carried on a mail car and supported beneath the floor of such car, the upper part of the receiver being in communication with the car through the floor thereof, a closure for the receiver, a trunk hinged to said receiver and in communication whereby to deliver the mail bags thereto, the lower end of the trough having a curved end adapted to dip down into the trough to receive the mail bags deposited therein, a roller carried by the free end of the trunk and arranged to come in contact with the floor of said trough, a band passing about the free end of said trunk, a tongue extending upwardly from said band, a rod having a bifurcated end pivoted to said tongue, the floor of the car having a recess for receiving said rod when in the horizontal position, a perforated extension on said rod, a pivoted catch mounted on the car and adapted to engage the perforated extension to hold the rod horizontally and the trunk elevated, a projection on said catch for operating same, a spring for holding the catch in the engaged position, and toggle rods pivoted centrally together and having their ends pivoted respectively to the car and the free end of said trunk and adapted to brace the latter when in the lowered position, substantially as described.

engage the perforated extension to hold the rod horizontal and the trunk elevated, a projection on said catch for operating same, and a spring for holding the catch in the engaged position, substantially as described. 45

4. In an apparatus for railway mail delivery, the combination of a trough built in the roadway and having sloping ends, platforms extending from the sloping ends and having downwardly bent extremities, a mail bag receiver carried on a mail car and supported beneath the floor of such car, the upper part 55 of the receiver being in communication with the car through the floor thereof, a closure for the receiver, a trunk hinged to said receiver and in communication whereby to deliver the mail bags thereto, the lower end 60 of the trough having a curved end adapted to dip down into the trough to receive the mail bags deposited therein, a roller carried by the free end of the trunk and arranged to come in contact with the floor of said 65 trough, a band passing about the free end of said trunk, a tongue extending upwardly from said band, a rod having a bifurcated end pivoted to said tongue, the floor of the car having a recess for receiving said rod 70 when in the horizontal position, a perforated extension on said rod, a pivoted catch mounted on the car and adapted to engage the perforated extension to hold the rod horizontally and the trunk elevated, a projection on said catch for operating same, a 75 spring for holding the catch in the engaged position, and toggle rods pivoted centrally together and having their ends pivoted respectively to the car and the free end of said trunk and adapted to brace the latter when in the lowered position, substantially as described. 80

In testimony whereof, I affix my signature.

LEWIS HENRY LLOYD.
